UNITED STATES PATENT OFFICE

2,664,840

SEWING MACHINE THREAD CONTROL

Michael Joseph, West Roxbury, Mass.

Application May 10, 1949, Serial No. 92,290

8 Claims. (Cl. 112—219)

1

The present invention relates to a sewing machine and more particularly to a means for stopping the machine when the thread making the stitch is broken.

The present means should be distinguished from that in which an indicator, as for instance, a bell is sounded, to tell that the thread of the machine is broken so that the machine operator will stop the machine when the indication has been given.

While such a system is satisfactory in some cases, it nevertheless fails to accomplish the desired results in many other cases, particularly where the sewing machine is a high speed machine, where the machine may be operated automatically, or where it is particularly desirable to stop the machine very quickly and in a given position. It is of course obvious that if the sewing machine continues to operate with the thread broken, there will be either no stitch at all, in which case the needle would continue to pierce the material and therefore make unnecessary holes, or the stitching will be imperfect due to the lack of one of the threads. In the present invention the machine is promptly stopped, in fact, it is stopped in such a position that the needle may be readily threaded. The means employed in the present invention are applicable to all types of sewing machines whether using a bobbin or a looper or any type of sewing machine in which a thread is fed in the operation of the machine. The means of the present invention are mechanical in character, positive and operate upon the breaking of a thread to actuate means which disengages a clutch on the driven shaft of the machine from the power source and shortly thereafter halts the rotation of the driven shaft in such a position that the reciprocating needle is at the top position away from the material. The needle in this position is ready to be threaded without turning the machine even a part of a turn.

The present invention is particularly useful in so-called power machines which operate so rapidly that even though the machine is being watched by the operator, he may not be able to stop it before a great number of false stitches have been made subsequent to the break in the thread. The mechanism of the present invention will not only operate to stop the sewing machine where the needle thread breaks, but the mechanism will also be actuated by any other break which releases the tension on the needle thread. Where the bobbin thread breaks, it invariably happens that the needle thread becomes

2

loose. In other types of sewing machines this also happens, so that the present invention is useful in stopping the operation of the sewing machine where any one of the threads in breaking, releases the tension of the thread with which the present mechanism is associated. While in the embodiment shown in the present invention the means for stopping the machine are shown in conjunction with the thread feed for the needle, it may similarly be used for thread otherwise supplied in the system and it may also be used for machines operating more than one needle in which case a break in any one of the threads may operate to stop the machine.

These advantages and other features of the present invention will be more readily appreciated and understood from the description in the specification forming a part of this application when taken in connection with the drawings illustrating an embodiment of the same, in which—

Figure 1 shows a view of the invention partly in perspective and part schematically as applied to a sewing machine.

Figure 2 is a detailed view of a detail looking down at the top of Figure 1.

Figure 3 is a view taken on the line 3—3 of Figure 2.

Figure 4 is a side elevation partly in section as viewed from the right of Figure 1.

Figure 5 is a view similar to Figure 4 but showing the mechanism in another position.

Figure 6 is a perspective fragmentary sectional exploded view of certain details of the invention.

Figure 7 is a perspective exploded view of some of the elements shown in Figure 6 as viewed from the left of Figure 6.

Figure 8 is a fragmentary detail of the front needle drive end of the machine shown in front elevation, and

Figure 9 is a more complete view of the detail shown in Figure 8 shown as a side elevation.

In the arrangement indicated in the drawings, the machine as a whole is indicated at 1. The needle thread 2 for this machine may come from a spool not shown, to the adjustable disc tensioner 3, whence it passes over an arm 4 projecting from the pivoted lever 5 through an eyelet 6 through guides 7 and 8 on the needle post and through the eye of the needle 9.

In the present invention, two threads are indicated. The second thread 10 passing through the tension member 3' over the arm 4', through the eye 6', and then similarly threaded as the

thread 2 to a second needle, not shown in the drawings. The levers 5 and 5' are similar in construction and operate independently in the same manner, as in fact the whole system, so that only one side of the thread control elements will hereafter be described. The lever 5 is pivotally journaled in a support 11 and has at its other end, a weight 12, which normally unbalances the lever so that gravity pulls the weight 12 downward and the forward end of the lever upward except when the thread 2 holds the forward end of the lever down. When the thread breaks, the forward end of the lever will fly up and strike the arm 13 which extends over the forward end of both levers 5 and 5' so that when the forward end of either lever rises, it will hit the arm 13. The arm 13 is adjustably attached in the slot 15 by means of the nut 14 at the side of the pivoted lever 16 which is pivoted at the top of a post 17 in a slot in the post by means of the pin 18. The rear end of the lever 16 is attached to a member or post 19 as indicated more clearly in Figures 1, 2, and 3. The post 19 is provided with a slot 20 which is bridged at the top by a pin 21, while the rear end of the lever 16 is provided with a hook-like member 22 which may be inserted in the slot beneath the pin 21, thus permitting the member 19 to rest fairly freely in a hole 23 (see Figure 4), at the free end of an L-shaped lever 24. The member 19 is formed with a shoulder 25 and a centrally located pin 26 engaging in the hole 23 and projecting from the underside of the end 27 of the lever 24. Normally the lever 16 is so balanced that the forward end carrying the arm 13 is inclined downwards in which position the pin 26 is held in its highest position as viewed in Figure 4. When the arm 13 has been hit by the lever 5, it will fly upwards sending the pin 26 downwards in a position to be engaged by the projecting boss 53 of the rotating clutch member 29. (See Fig. 5.)

These elements may best be described in conjunction with the additional showing of Figures 6 and 7. In Figure 6, a portion of the machine frame is indicated at 30. On the end face are two projecting, diametrically positioned pins 31 and 32. These pins may project from the smooth inner face 33 of the machine frame which may also serve as a bearing for the driven shaft 34 which connects with the front of the machine for operating the needle bar and other mechanism. The shaft 34 is shown broken away in Figure 6 and indicated in dotted position. Fitting over the shaft 34 and in adjacent opposing position to the surface 33 is a cam and reset operating member 35. The drive shaft 34 extends through the member 35. The cam 35 has on the face adjacent the face 33 two diametrically opposite concave recesses 36 and 37 in a position opposite the position of the pins 31 and 32. When the pins 31 and 32 lie in these concave recesses, the face 38 of the cam member comes substantially flush against the surface 33. However when the member 35 is turned a slight angle about the shaft 34, the pins 31 and 32 move out of the concave recesses 36 and 37, thus forcing the member 35 to the right as viewed in Figure 6.

Lying in face contact with the side 39 of the member 35 is the clutch member 29. This clutch member 29 is provided on its left face as seen in Figure 7, with a ball-bearing ring 41, engaging in slight recesses 42 on the surface 39 of the member 35. The clutch element 29 is also provided with a key way 43 in which is situated the key 44 (see

Figures 4 and 5), which at all times locks the clutch to the shaft 34 so that the clutch is always locked to the driven shaft, but permitting a small longitudinal movement with respect to the shaft. The other surface 40 of the clutch is provided with a suitable friction material which may be similar to that used as a brake lining and this may be attached to the surface of the clutch by the screws 45 set deeply in the material. Fitting over the disc clutch and also concentrically mounted on the shaft is a flywheel 46. This flywheel is provided with a collar 47 on its inner side which serves as a cover for the clutch member and also as a pulley for a belt which fits in the slight concave outer ring 48. The flywheel is mounted freely on the shaft 34 and drives the clutch 29 when the friction surface 40 of the clutch engages the inner surface 49 of the flywheel adjacent to it. On the outer side of the flywheel 46 is a sleeve member 50 which may be locked in place on the shaft 34 by a set screw 51. The sleeve 50 may be provided with a groove 52 to receive a belt for driving a feed mechanism such as a feed of material to the machine. Since the flywheel 46 is the driving member and the clutch 29 the driven element which connects with the driven shaft 34 at all times, the rotation of the shaft 34 will stop when the flywheel 46 and the clutch 29 disengage. The elements line up on the shaft 34 in such a way that when the machine is operating, the member 35 has its concave recesses 36 and 37 out of engagement with the pins 31 and 32. In this position the surface 40 of the clutch 29 will be held firmly in contact with the surface 49 of the flywheel 46 so that when the flywheel is driven, the shaft 34 will rotate with it.

It is obvious that in order to disengage the clutch the member 35 must be rotated from a position in which the pins 31 and 32 do not engage the recesses 36 and 37 to one in which they do. This is taken care of by the operation of the lever 24 through the action of the pin 26 projecting through the hole 23 in the end 27 of the lever 24. The clutch 29 for this purpose carries a projecting boss 53. The member 35 as it rotates comes in contact with the end of the pin 26 if this is in a projecting position due to the break of the thread and the upward motion of the forward end of the lever 16. The L-shaped lever 24 is pivoted at 54 to a fixed member attached to the machine by the screw 55. The lever 24 is tensioned to this fixed member by the spring 56. In normal position before any shut down of the machine occurs, the lever 24 holds the cam and reset member 35 in a downward position as seen in Figure 4. This is accomplished by the engagement of a pin 57 projecting from the member 35 and engaging in a recess 58 in the side of the long arm of the L-shaped lever. The cam member 35 is held by the spring 59 so as to tension the pin 57 in the latching recess 58. The cam member 35, in the position shown in Figure 4, also bears against the shoulder of the pin 60 which is forced upward against the lower edge 61 of the cam member 35 by the helical spring 62 acting on the piston 63 in the well 64. The piston 63 is connected by the rod 65 to the bottom end of the pin 60. The clutch element 29 which carries on its external surface, the boss 53, is normally rotated in the direction of the arrow A (see Figures 4 and 5), and in normal operating position, the pin 26 is just a little below the end 27 of the L-shaped lever so that the projection 53 on the clutch 29 will clear the pin 26 as it rotates.

In the tilted position of the cam plate 35, shown

in Figure 4, the boss or projection 53 will also clear the inclined surface of the pin 60. In Figure 4 the two dotted areas indicate the recesses 36 and 37, which it will be noted are not in engagement with the pins 31 and 32 and therefore under this condition the clutch 29 is held in engagement with the surface 49 at the center of the flywheel.

If a thread of the machine breaks, as for instance, the thread 2, then the pin 4 will fly upwards, hitting the bar 13, causing the lever 16 to rise at the front end and the pin 26 to drop at the rear end below the inner surface of the end 27 of the L-shaped lever. This condition is shown in Figure 5. When therefore the pin 53 on the clutch comes in contact with the end of the pin 26, the L-shaped lever 24 will be turned about its pivot 54 in a counterclockwise direction, disengaging the pin 57 of the cam plate 35 from the L-shaped lever and permitting thereby the cam plate 35 to turn in a clockwise direction bringing the recesses 36 and 37 into engagement with the pins 31 and 32. This will relieve contact between the clutch face 49 and the face 49 and permit the clutch 29 to move away from the face 49 of the flywheel, thereby disengaging the driven shaft 34 from the driving system. The pin 68 projecting from the cam plate 35 limits the clockwise movement of the cam plate 35 when it comes in contact with the outside of the L-shaped lever. The pin 53 continuing its rotation now comes in contact with the corner of the pin 68 since this moves upward as the cam plate takes a level position, and brings the clutch to rest in the position shown in Figure 5. This position corresponds to the position shown for the needle bar in Figure 9 which is in its highest spot of its reciprocating cycle.

The arrangement indicated in Figures 8 and 9 is a usual arrangement used in sewing machines. The shaft 34 drives the eccentric cam 67, which in turn drives the crank 68 to which the needle bar 69 is attached.

When the thread is broken, the machine should be threaded in the usual manner. In order to hold the lever 16 down until this is accomplished, the bar 71 may be turned until it lies over the forward end of the lever 16. The bar may be tightened in this position by the thumb nut 72. After the machine has been threaded, the bar 71 may be moved away from the lever 16 and then the handle 70 of the cam plate should be moved downward which will engage the clutch with the driving surface of the flywheel and thereby restart the machine.

It will of course be noted that moving the handle 70 downward will release the pin 68 from the projection 53 and the pin 26 will normally be raised when the bar 16 falls to its normal downward position. The driven shaft 34 as has been previously stated, is capped by the sleeve member 59, which holds the flywheel in position so that the surface 49 of the clutch may be pressed against the surface 49 of the flywheel for providing the driving coupling.

It should also be noted in the arrangement in the present invention that the thread tensioning members 3 and 3' are placed between the feed spool and the needle so that the thread will always be under tension during its feeding to the needle.

Having now described my invention, I claim:

1. In a device for stopping the operation of a sewing machine upon the breaking of a sewing thread of the machine, a driven shaft having a clutch plate keyed for a small longitudinal motion

with respect thereto, a normally free running driving pulley concentrically mounted on the driven shaft and having a surface in opposed position to said clutch plate, an operating cam plate concentric with said driven shaft and manually positioned for engaging said clutch plate with said opposed surface of said pulley, latch means retaining said cam plate under spring tension in said manually placed position, means operated by the breaking of the thread for releasing said cam plate and permitting said clutch to move axially on said driven shaft out of engagement with the opposed surface of said pulley, and means positioned upon the motion of the cam plate to engage said clutch for stopping the rotation of the driven shaft.

2. In a device for stopping the operation of a sewing machine upon the breaking of a sewing thread of the machine, a driven shaft having a clutch plate keyed for a small longitudinal motion with respect thereto, a driving plate having a friction surface concentrically positioned on said shaft in opposed position with respect to said clutch plate, a cam plate also concentrically positioned on said shaft on the other side of said clutch plate from that of the driving plate, means associated with said cam plate comprising a pair of fixed pins and a pair of recesses on one face of the cam plate adapted to engage in said fixed pins in one angular position of said plate and in a second angular position to be longitudinally moved along the driven shaft, said cam in the second position moving said clutch plate and the friction surface of said driving plate into engagement with each other and means actuated upon the breaking of the thread for permitting moving of said clutch plate from the second position to the first for disengaging the driven shaft from the driving plate.

3. In a device for stopping the operation of a sewing tension machine upon the breaking of a sewing thread of the machine, a driven shaft having coaxially mounted therewith a clutch plate keyed for a small longitudinal motion with respect thereto, said clutch plate having a projection extending outward from the periphery thereof, a driving plate positioned in opposing position to said clutch plate, an operating cam plate coaxial with both said other plates, means associated with angular positions of the cam plate for holding in one position the clutch plate and driving plate in engagement with one another and in another position permitting their separation respectively, an inverted L-shaped spring tensioned lever pivoted at one end to the sewing machine for movement in a plane parallel to said cam plate and closely positioned thereto, a second lever having at a free end a pin extending through a hole at the unpivoted end of said first lever, said pin normally spaced in the same plane but clear of a projection on said clutch, a pin projecting from said cam latching into a recess in said L-shaped lever, means spring tensioning said cam with the pin in said latched position and means actuated upon the motion of said second lever for engaging said first mentioned pin with the projection on said clutch and moving said cam plate from the first position to the second, and means actuated thereby for engaging said projection for stopping said driven shaft.

4. A device for stopping the operation of a sewing machine upon the breaking of a sewing thread of the machine which comprises a free running drive member associated with the machine, a thread feed mechanism having a lever

member with one end in a raised position when the thread is being fed, a needle and needle reciprocating mechanism through which said thread is fed, a driven member for operating the machine mechanism including said thread feed mechanism and said mechanism for the reciprocating of the needle and the feeding of the thread, said drive element and driven member having a concentric axis, a clutch member mounted on said driven member and keyed thereto, means holding said clutch member in engagement with the free running drive element, means operated when said end of the lever is lowered upon the breaking of the thread for releasing the pressure holding said clutch member along said concentric axis in engagement with the free running drive element, said clutch member having a projection extending outward from its periphery and a spring pressed pawl moved in position by said last mentioned means acting in conjunction with said projection on said clutch for stopping said driven member in a desired position.

5. In a device for stopping the operation of a sewing machine upon the breaking of a sewing thread of the machine, a driven shaft having a clutch plate keyed for a small longitudinal motion with respect thereto, a driving plate concentrically positioned with respect to said clutch plate, a cam plate also concentrically positioned therewith, means operative in two angularly different positions of said cam plate for forcing said driving and clutch plates into engagement and for releasing said force whereby said driving and clutch plates may move out of engagement respectively, and means actuated upon the breaking of the thread for shifting said means operative in two angularly different positions in said cam plate from the first angular position to the second.

6. In a device for stopping the operation of a sewing machine upon the breaking of a sewing thread of the machine, a driven shaft having a clutch plate keyed for a small longitudinal motion with respect thereto, a driving plate concentrically positioned with respect to said clutch plate, a cam plate also concentrically positioned therewith, means operative in two angularly different positions of said cam plate for forcing said driving and clutch plates into engagement and for releasing said force whereby said driving and clutch plates may move out of engagement respectively, means actuated upon the breaking of the thread for moving said means operative in

two angularly different positions of said clutch plate from the first angular position to the second, and means automatically positioned with respect to the driven shaft upon the motion of the cam plate for stopping the motion of the driven shaft in a desired position.

7. In a device for stopping the operation of a sewing machine upon the breaking of a sewing tensioned thread of the machine, a driven shaft having coaxially mounted therewith a clutch plate keyed for a small longitudinal motion with respect thereto, a driving plate positioned in opposing positions to said clutch plate, an operating cam plate coaxial with both said other plates for moving said clutch plate longitudinally along said shaft for bringing it into engagement and out of engagement with said driving plate and means actuated when the tension on the thread is released for actuating said cam plate including a pivoted lever carrying a pin restrained by said tensioned thread, a spring tensioned lever having means positioned for restraining said cam plate to hold said clutch plate and driving plate in engaging position through which last mentioned lever said pin passes and means operated by the dropping of said pin when said first pivoted lever is unrestrained for releasing said second lever and moving said cam to a disengaging position of said clutch plate from said driving plate.

8. In a device as set forth in claim 7 including a plurality of levers, each held in restrained position by separate threads each under tension and means positioning said first mentioned lever to be actuated in any of said plurality of levers for untensioning of any of said threads for stopping the operation of the sewing machine.

MICHAEL JOSEPH.
